UNITED STATES PATENT OFFICE.

CLEMENT A. HARDY, OF CHICAGO, ILLINOIS, ASSIGNOR TO WHITING FOUNDRY EQUIPMENT COMPANY, OF HARVEY, ILLINOIS, A CORPORATION OF ILLINOIS.

SCREW-JACK LOCOMOTIVE-HOIST.

1,085,734.

Specification of Letters Patent.

Patented Feb. 3, 1914.

Application filed April 28, 1913. Serial No. 764,140.

To all whom it may concern:

Be it known that I, CLEMENT A. HARDY, a citizen of the United States, residing at Chicago, in the county of Cook and State 5 of Illinois, have invented a certain new and useful Improvement in Screw-Jack Locomotive-Hoists, of which the following is a specification.

This invention relates to hoisting devices 10 for use in engine houses and the like for lifting a locomotive, particularly an extra large one, such as of the Mallett type, off the track to a position where the wheels may be removed preparatory to repairs and overhauling.

The object of this invention is to provide a plurality of lifting devices, preferably three, spaced along a portion of the track over which the locomotive is to move, one of 20 the lifting devices being located in a fixed position with reference to the track, while the other two or more devices are adjustable toward and from the stationary lifting device so as to accommodate and fit locomotives 25 of different sizes, all of the lifting devices being, when desired, simultaneously operable from a single source of power, usually a shaft.

A further object of the invention is to so 30 construct and arrange the lifting devices that they may all be lowered to a normal or first position in which they form a part of the track over which the locomotive passes in entering the device and, after the locomotive has passed to position, may be operated as lifting devices therefor, in the manner heretofore described.

The invention consists in a device capable 40 of carrying out the foregoing objects, which can be easily and cheaply made and installed, which is satisfactory in operation, and not readily liable to get out of order.

More in detail, the invention consists in 45 the use of horizontal lifting bars extending crosswise of the track, supported at the opposite ends outside the track by lifting mechanisms movable in the manner described, the bars being lowerable into openings cut in the track and the openings being closed 50 by rail devices carried by the lifting bars so that when the bars are in lowered position the locomotive may pass along these tracks over the lifting bars to a desired position and thereafter the lifting bars may be first moved upward out of the openings in the

track, and thence the two outer bars may be moved horizontally to required positions for lifting the locomotive, and that when each of the lifting bars has been thus adjusted to the locomotive to be lifted they may all be 60 simultaneously elevated through the action of one common source of power.

The invention further consists in special features which will be hereafter described and claimed.

In the drawings which represent a physical embodiment of the preferred form of this invention; Figure 1 is a plan view of the device. Fig. 2 is a corresponding side view. Fig. 3 is a sectional end view of a 70 portion of the track and one of the lifting bars, and one lifting device or jack applied thereto. Fig. 4 is a central sectional detail view through one of the lifting jacks proper.

The main track rails 10 on which a locomotive passes to lifting position and on which it stands before the lifting operation begins is clearly shown in Fig. 1, and they may be located in an engine house or anywhere else where it is desirable to lift the 80 locomotive partially or wholly from the tracks. As the device is primarily intended for extra heavy locomotives of the Mallett type, three horizontal lifting bars 12, 13, and 14 are provided of such a length that, as 85 shown, they extend well outside the track rails 10. These bars are preferably located longitudinally of the tracks 10 so that, as near as the designer can determine, the bar 13 will engage the central portion of the locomotive to be lifted and the bars 12 and 14 will approximately engage end portions 90 of the locomotive frame. The bars are also let into recesses 16 in the track rails 10 and the foundations therefor, to such an extent 95 that rail sections 18, secured by any suitable means to the tops of these bars, will, when the bars are in lowered or normal position, register with the track members 10 and thus form a continuous track over which a locomotive may pass to or from lifting position without in any way engaging or otherwise interfering with the lifting bars 12, 13, or 14, and the parts to be hereafter described 100 which operate the lifting devices. Rising from suitable foundations at opposite ends of the central bar 13 are stationary upright supports 24 in which are suitably mounted vertical lifting screws 26, one for each end 105 of the bar 13. Similarly opposite ends of the 110

bars 12 and 14 are carried by screws 26 guided in uprights 30 which are mounted upon truck frames 32, one located at each side of the main track rails 10. Each of the two outer truck frames 32 is supported upon a suitable set of wheels or rollers 34 movable along supplemental track rails 36 provided for the purpose, as shown, parallel to the main track rails 10. By the use of these supplemental track rails the bars 12 and 14 may, whenever lifted high enough to clear the rails 10, be moved longitudinally of said track rails 10 so as to longitudinally adjust the lifting bars to proper lifting position for application to the locomotive body 38, one of whose many possible forms is suggested in dotted lines in the upper portion of Fig. 2.

The trucks and lifting devices may, if desired, be made exactly as shown, described and claimed in the patent application of Fred A. Rundle for screw jack locomotive hoists, Serial Number 665,082, filed December 11, 1911, wherein means is provided for selectively applying power for operating the lifting mechanism or moving the truck by power along their respective tracks. In the device here shown in the drawings, the trucks 32 are movable along their respective tracks 36 by the use of levers 40 operating ratchet devices 42 carried by the shaft 46. Any method of moving the trucks along these tracks may be used without departing from this invention.

Mounted in any sort of suitable bearing 48 on opposite sides of the track 10 are two parallel rotatable shafts 50 driven by any suitable source of power at equal speeds. In the particular case here illustrated these shafts are driven by a motor 52 which operates them through the two sets of bevel gearing 53 and 54 connected together by the shaft 55 which is located below the rails 10 so as to be out of the way of a passing locomotive.

At the base of each one of the vertical screws 26 is a worm wheel 56 rigidly connected to the screw 26 by any suitable means and meshing with a worm 58, journaled upon the adjacent shaft 50, and carrying at its end any suitable clutch jaw 60. Meshable with this jaw is a clutch member 62 slidably but non-rotatably mounted upon the shaft 50 by any of the well known methods. This clutch jaw 62 is movable into and out of mesh with jaw 60 by the operation of a hand lever 64 pivoted upon any suitable support, as for instance 66, a pin 68 which enters an annular notch 70 in the jaw 62 so that moving the lever 64 will move the clutch jaw back and forth along the shaft without interfering with the rotation of the clutch member by the shaft.

From the description of the foregoing parts, which are all well known in the art, it is obvious that the operator may, by operat-

ing a particular lever 64 to throw its particular clutch jaw 62 into or out of mesh with the jaw 60, as the case may be, stop or start the rotation of the particular screw 26 which is in operation with that particular clutch jaw 60 with which the operator is working. As all six of the lifting screws 26 are provided with the mechanism just described, it is obvious that by having two operators, one on each side of the track, manipulate the levers 64 of a particular lifting bar, as for instance 12, the bar and the load upon it may be moved up and down at the will of the operator independently of the other bars 13 and 14. It is also obvious that by having an operator at each of the six levers 64 simultaneously and correspondingly operate said six levers, all three of the bars 12, 13 and 14 may be simultaneously moved in either direction depending upon the rotation of shafts 50, or brought to rest as the commanding workman may direct. The same result may also be secured by having a single operator first stop the motor and shaft, then throw in all the clutches one after the other and then start the motor again in the desired direction.

In order to do away with objectionable springing in the end portions of the shafts 50 adjacent to the trucks 32, a supplemental support 72 mounted upon wheels 74 movable along the adjacent tracks 36 is provided. The particular shaft section 50 to which these devices are applied rotates freely in the upper portion of the support 72 and the support may be moved along the track 36 to a position where it is midway between the adjacent truck 32 and the next adjacent stationary support 48.

The trucks 32 and supports 72 may be connected by chains, rods or links 100 as suggested in the upper left hand corner of Fig. 1 so that they move more or less in unison as desired.

It will be noticed that the middle lifting bar 13 is carried from a stationary support, thereby doing away with the expense of trucks at opposite ends of the bar and what is more important, tending to steady the entire mechanism during the operation of raising a locomotive thus preventing longitudinal movement of the locomotive and any of the lifting parts after the lifting operation has actually begun.

In the operation of the entire device, the various lifting bars are moved in the manner described either independently or simultaneously to the above described normal position so that each of the bars is in such a position below the track rails 10 that the track sections 18 carried by them are in register with the track rails 10 so as to permit the passage of the locomotive along the tracks 10. The locomotive to be lifted is now moved along the track rails 10 until its

central body portion 38 is directly over the central lifting bar 13. The operators now independently or in combination raise each of the lifting bars 12 and 14 so that they are above and clear of the track rails 10 but are not yet high enough to contact with the end body portions 38 of the locomotive. They then by use of ratchet levers 40 move the lifting bars 12 and 14, which are up to this time outside the ends of the locomotive, along the tracks to positions where the respective bars register with suitable body portions of the locomotive to be lifted. The operators then either independently or simultaneously move these respective bars 12 and 14 upward until they are in lifting contact with their respective body portions of the locomotive. Then proper adjustment of the supports 72 is made whereupon all of the levers 64 are thrown to lifting position and as the different sections of the shafts 50 rotate simultaneously all parts of the locomotive are simultaneously lifted at the same rate of speed, thereby reducing the strain upon it to the lowest point. When the locomotive has reached the proper position the motor 52 is stopped thereby sustaining the locomotive in that position and the wheels may be rolled away. When it is desired to lower the locomotive, motor 52 is operated in the reverse direction until the locomotive rests upon the rails 10, whereupon the manipulations heretofore described are reversed to return the various lifting bars to their normal position with their rail sections 18 in register with the adjacent portions of the track whereupon the locomotive may move along the track rails 10 off from and clear of the parts which have been heretofore described. The trucks on which the locomotive is thus moved away may be its regular ones or only temporary ones.

Having thus described my invention, what I claim as new and desire to secure by Letters Patent, is:—

1. In a device of the class described the combination with a track for an object to be lifted, three lifting devices along the track, one located on stationary supports between the other two, the latter two being movable along the tracks toward or from the central lifting device, and means for then simultaneously operating all of the three lifting devices at the same rate of speed.

2. In a device of the class described, in combination with a track for an object to be lifted, a lifting device mounted upon a stationary support near the center of a length of the track, two other lifting devices on opposite sides of the first lifting device and near the end of said track length movable toward and from the central lifting device, and a power shaft adapted to then simultaneously operate all of said lifting devices at the same rate of speed.

3. In a device of the class described, a portion of track on which an object to be lifted may rest, a lifting bar near the center of said track vertically operable to lift the center of the object to be lifted and carried upon stationary fixed supports outside the track, two other lifting bars, one near each end of said track operable to lift the respective ends of the object upon said track carried upon truck devices outside the track movable parallel to said track to adjust the position of said end lifting bars with reference to the length of the object which is to be lifted, and power means adapted, when the various lifting bars have been adjusted longitudinally of the track to simultaneously and correspondingly operate all three lifting bars, for the purposes set forth. 70 75 80

4. In combination with a pair of track rails, a lifting bar extending across said rails and movable vertically through openings in said rails from a position below to a position above said rails and vice versa, rail members carried by the bar adapted, when the bar is in one position, to close the spaces in said rails through which the bars move so as to permit the passage of an object to be lifted by said bar along said rails, means for lifting said bar located along said bar outside the planes of said rails and means for transporting said lifting means and the supporting bar movable parallel to the rails after the bar has been lifted above the rails. 85 90 95

5. In combination with a pair of track rails, a lifting bar extending across said rails and movable vertically through openings in said rails from a position below to a position above said rails and vice versa, and rail members carried by said bar adapted, when the bar is in one position, to close the space in said rail through which the bar moves so as to permit the passage of an object to be lifted by said bar along said rails, a truck supporting said lifting means movable when the bar is lifted above the rail longitudinally of said track rails, and means operable at will in any position of the truck for lifting said bar. 100 105 110

6. In a device of the class described, a portion of a track on which an object to be lifted may rest, three lifting bars of greater length than the width of the track extending across the track in recesses which normally permit their lying below the track and clear of an object to be lifted passing on said track, rail devices carried by said lifting bars registering with openings in the track formed to permit the lifting bars moving from said normal position to a position wherein said bars are above and clear of the tracks and thus in said normal position making the tracks continuous, a support for the opposite ends of the central bar, a supporting device for the opposite ends of each of the other two bars capable of being moved 115 120 125 130

toward and from the central bar, lifting devices for said bars carried by the respective supporting devices, and means operable at the will of an operator adapted to independently or simultaneously and correspondingly operate said lifting devices, all for the purposes set forth.

In witness whereof, I have hereunto subscribed my name in the presence of two witnesses.

CLEMENT A. HARDY.
